UNITED STATES PATENT OFFICE

99,117

DESIGN FOR A GOLF TEE

George W. Drinkert, Highland Park, Mich.

Application October 12, 1935, Serial No. 58,971

Term of patent 7 years

To all whom it may concern:

Be it known that I, George W. Drinkert, a citizen of the United States, residing at Highland Park, in the county of Wayne and State of Michigan, have invented a new, original, and ornamental Design for a Golf Tee, of which the following is a specification, reference being had to the accompanying drawing, forming part thereof.

The figure is a perspective view of a golf tee showing my new design.

I claim:—

The ornamental design for a golf tee, as shown.

GEORGE W. DRINKERT.
